Attorney, Agent, or Firm—Fisher, Christen & Sabol***[57] CLAIM**

The ornamental design for a bath tub, as shown and described.

DESCRIPTION

FIG. 1 is a top plan view of a bath tub showing my new design;
 FIG. 2 is a cross-sectional view thereof as taken along line 2—2 in FIG. 1;
 FIG. 3 is a top perspective view thereof;
 FIG. 4 is a left side elevational view thereof, the right side being a mirror image; and
 FIG. 5 is a rear elevational view thereof.

FIG. 1

FIG. 3

FIG. 2

FIG. 4

FIG. 5
